STEPHEN P. M. TASKER, OF PHILADELPHIA, PENNSYLVANIA, ASSIGNOR
TO MORRIS, TASKER, & CO., OF SAME PLACE.

Design No. 4,154, dated June 14, 1870.

DESIGN FOR A TRADE-MARK.

The Schedule referred to in these Letters Patent and making part of the same.

I, STEPHEN P. M. TASKER, of the city of Philadelphia and State of Pennsylvania, have invented and produced a new and original Design for a Trade-Mark, of which the following is a specification.

My design consists of a stamp having on its face
M & Co., as shown in the accompanying drawings.
I claim as my invention—

The design for a trade-mark, as described and shown.

In testimony that the above is my invention I have hereunto set my hand this 26th day of May, 1870

Witnesses: STEPHEN P. M. TASKER.
